BLADE MAGAZINE

Nicholas Testi, Boston, Mass., assignor to Gillette
Safety Razor Company, Boston, Mass., a cor-
poration of Delaware

Application May 4, 1940, Serial No. 333,346

7 Claims. (Cl. 206—16)

This invention relates to magazines for blades, such as safety razor blades. It consists in a magazine of new and improved construction, inexpensive to manufacture and convenient to fill with a supply of sharp edged blades, effective to guard and protect the blade edges and accurate in controlling the discharge of one blade at a time for use in a safety razor or for any other purpose.

Safety razor blades of thin sheet steel, often as thin as ".004" and manufactured with an exceedingly fine sharp shaving edge, are difficult to pack and distribute without dulling and are dangerous to handle in presenting new blades to a safety razor or removing used blades for cleaning or replacement.

I have discovered a construction of magazine which is entirely satisfactory in the respects noted and which is also proof against the annoyance of jamming of blades in the discharge opening. This has been a serious defect in magazines heretofore available for it frequently happens that two blades at a time are forced into the discharge opening and jammed so that it is impossible to eject a single blade and serious danger of cutting is likely when the operator attempts forcibly to clear the magazine.

With these objects in view an important feature of my invention consists in a magazine comprising an elongated enclosure having a slot in its top wall and a discharge opening in one end and provided with a pin upstanding in the bottom of the magazine beneath the slot and serving to locate the blade stack and also to gauge the width or depth of the discharge opening. Blades of the stack may be made each with an end notch adapted to engage the pin and thus the blades are registered in superposed relation. The upper end of the pin, moreover, may be accurately terminated below the plane of the inner face of the top of the magazine by exactly the thickness of a single blade. The accurate determination of the gauging end of the pin is facilitated since it is in an accessible position beneath the slot in the top of the magazine. Accordingly, it may be conveniently reached by the inserting tools in the assembling operation and it may be reached by a grinding wheel after insertion so that its end face may be shaped and positioned with any desired degree of nicety. As a result of this construction it is impossible to introduce a second blade into the discharge opening until the first blade has been wholly ejected. Even if the feeding mechanism is operated accidentally to engage the

second blade in the stack that blade is positively held by the pin against movement until the preceding blade has been fully discharged and removed from the space between the gauging end of the pin and the top of the magazine. Only then can the second blade engage the top of the magazine and clear the end of the gauge pin.

These and other features of the invention will be best understood and appreciated from the following description of a preferred embodiment thereof, selected for purposes of illustration and shown in the accompanying drawing, in which:

15 Fig. 1 is a plan view of the magazine on an enlarged scale;

Fig. 2 is a corresponding view in front elevation;

Fig. 3 is a fragmentary view in longitudinal section on still larger scale;

20 Fig. 4 is a view in cross-section on the line 4—4 of Fig. 3; and

Fig. 5 is a view in elevation showing the magazine operatively connected to a safety razor.

25 The magazine herein shown may be bent to shape from a blank of thin sheet metal or it may be moulded from any suitable thermo-plastic material. It comprises an elongated shell 10 of rectangular outline forming an enclosure of which the top is formed by longitudinally in-turned flanges 11 and 12 separated by a wide centrally located slot which extends from one end to the other of the shell. The flanges 11 and 30 12 form a guideway for a feed slide 15 which is provided with downwardly extending undercut walls fitting the flanges 11 and 12. The flanges are provided at their inner corners at both ends of the magazine with stops 13 and 14 in the shape of upturned ears which limit the path of movement of the feed slide 15.

35 Set in the bottom of the magazine centrally and in line with the longitudinal axis of the slot or opening between the flanges 11 and 12 is a pair of upstanding pins 16 and 17. The pin or post 16 is located near the forward end of the magazine and terminates at its upper end below the plane of the inner face of the flanges 11 and 12 by an amount equal exactly to the thickness of one of the blades for which the magazine is designed. The end of the pin, therefore, in co-operation with the flanges 11 and 12 gauges the depth of the discharge opening in the left-hand end of the magazine. The pin 17 at the rear 40 end of the magazine projects substantially above

the plane of the inner face of the flanges 11 and 12 and into the space which is bridged by the sides of the feed slide 15. The pin 17, therefore, effectively closes the rear end of the magazine. Within the magazine is located a curved leaf spring 18 which is arranged to bear upon the lowermost blade of the stack adjacent to its opposite ends and yieldingly to lift the whole stack, maintaining the uppermost blade in contact with the inner face of the flanges 11 and 12. The magazine is provided externally at its left-hand end with a tapering finger 19. This is adapted and shaped to be inserted in the safety razor for the purpose of temporarily separating the blade-clamping members and of registering the magazine in the proper position for presentation of a blade to the blade seat. The side walls of the feed slide form in effect a recess affording clearance in the slide for passing over the ends of the pins 16 and 17 and also providing a blade-pushing portion below each flange.

As shown in Fig. 5 the razor comprises a head 20 having a guard 21 and a co-operating clamping plate 22. The blade is inserted endwise between these two members while they are temporarily sprung apart by the insertion of the finger 19. At the conclusion of the blade-delivering step the magazine may be withdrawn and the clamping members allowed to engage and hold the delivered blade in shaving position.

The blades 23 herein shown are single-edged blades having a centrally disposed semi-circular recess in each end by which they may be registered vertically in a stack. As already stated the invention is not limited to blades of this particular design for it would be within the scope of the invention to modify the shape and dimensions of the magazine to accommodate blades of any other desired size or style.

The magazine is initially filled with ten or more blades by the manufacturer and these may be inserted one by one or inserted as a stack prior to the insertion of the pin 17. Within the magazine the blades 23 are positively retained in predetermined longitudinal and transverse position by the engagement of the pins 16 and 17 in the end recesses of the blades. At the same time the blades are free to move upwardly on the pins in response to upward pressure of the spring 18. As already intimated the loaded magazine may be wrapped and used as a container for distributing and dispensing blades to the user.

It will be noted that the flanges 11 and 12 and the side walls of the magazine extend to the right beyond the pin 17 sufficiently to support the feed slide 15 in a position beyond the end of the stack, this being the initial position of the feed slide. If it is desired to present a blade to the safety razor of Fig. 5 the magazine is presented with the finger 19 inserted in the manner already explained and then the feed slide is advanced from right to left. In this movement its flanges engage the unsharpened end of the uppermost blade in the stack. The feed slide passes over the pin 17 without obstruction and the blade is positively advanced toward the left passing out through the exit or discharge opening determined by the upper end of the pin 16 and the inner face of the flanges 11 and 12. The movement of the feed slide 15 should ordinarily be continued until the uppermost blade 23 has been fully ejected but if the feed slide is returned to its initial position before ejection of the uppermost blade has been completed, although the

feed slide now engages the second blade in the stack, it is unable to advance it because its foremost end is securely held by the pin 16. The second blade, moreover, is positively prevented from lifting by the portion of the uppermost blade still remaining in the magazine above the end of the pin. No jamming of blades, therefore, occurs in the discharge opening, but by the obstruction of the feed slide the attention of the user is drawn to the fact that the previous blade has not been fully ejected. The magazine may be then cleared either by drawing the uppermost blade out of the discharge opening by hand or by forcibly depressing the stack against the action of the spring 18 until the feed slide is again enabled to move forwardly above the second blade in the stack. When this occurs the feed slide again reaches the end of the unejected blade whereupon the ejecting operation may be completed in the regular manner. Ordinarily when a fresh blade is advanced to the blade seat of the razor the used blade is pushed out of the razor ahead of the fresh blade.

It will be noted that while the blades are held in the stack in the magazine by the pins 16 and 17 their sharp edges are positively retained out of contact with any part of the magazine enclosure although they are always free to move up or down on the pins 16 and 17 and to pass one by one above the end of the pin 16.

Having thus disclosed my invention and described the best way now known to me of putting it into practice, I claim as new and desire to secure by Letters Patent:

1. A magazine containing a stack of end notched safety razor blades, comprising an enclosure having spaced pins in its bottom between which the stack is registered and held by the end notches of the blades, the enclosure having spaced flanges in its upper wall which expose the ends of said pins, one pin reaching the plane of said flanges and the other pin terminating below said plane sufficiently to provide a discharge opening of the width of a single blade, and a feed slide movable on the flanges of the upper wall of the enclosure and bridging the ends of said pins.

2. A blade magazine comprising an elongated rectangular enclosure having a flanged top, a feed slide guided for limited longitudinal movement therein and having a blade-pushing portion projecting into the enclosure, and pins of unequal length set upright in the bottom of the enclosure and exposed at their upper ends between said flanges, one of said pins terminating below the plane of the inner face of said flanges by a distance equal to the thickness of a single blade, and the other being longer and closing the magazine at its inner end.

3. A magazine for safety razor blades, comprising a sheet metal enclosure open at both ends and having its top formed by opposed parallel flanges separated by a central opening, centrally disposed pins upstanding in the bottom of the enclosure and serving to locate a stack of end-notched blades with their sharp edges held positively out of contact with the walls of the enclosure, one of the pins closing one end of the enclosure and the other pin terminating below the flanges by the thickness of a single blade thus providing a discharge opening of that depth, and a feed slide movably mounted to slide on said flanges and shaped to bridge the ends of both pins in its movement and to engage a blade on both sides of the pin.

4. A magazine for safety razor blades, including in its structure an elongated enclosure having a top defined by spaced flanges extending inwardly from the sides of the enclosure so as to form a longitudinally extending slot, an up-standing pin at one end terminating below said flanges and defining therewith a discharge opening of substantially the width of a single blade, and a feed slide interfitting at its edges with said spaced flanges and having a blade-engaging portion movable inside the enclosure and recessed in its inner face to afford clearance for passing over the end of the pin while making feeding engagement with a blade in the magazine.

5. A magazine for safety razor blades, including in its structure an elongated enclosure having a top defined by spaced flanges extending inwardly from the sides of the enclosure and separated by a longitudinal slot, upright pins

set in the bottom of the enclosure, one of said pins terminating below the inner face of the flanges and the other above said face, and a feed slide undercut at its edges to fit said flanges and to extend partially within the enclosure, the slide being recessed to bridge the upper ends of said pins and to provide blade-pushing portions below each flange.

6. A magazine of the character defined in claim 5 in which the flanges extend outwardly for a distance sufficient to support the feed slide outside said longer pin.

7. A magazine of the character defined in claim 5 which has an elongated finger projecting from one end in a direction parallel to the path of the feed slide and of a blade ejected by the movement thereof.

NICHOLAS TESTI.
